UNITED STATES PATENT OFFICE.

ARTHUR THYLL, OF NEW YORK, N. Y., ASSIGNOR TO THE ELECTRIC CUTTER COMPANY, OF SAME PLACE.

CLOTH-CUTTING MACHINE.

SPECIFICATION forming part of Letters Patent No. 527,224, dated October 9, 1894.

Application filed November 7, 1891. Renewed March 17, 1894. Serial No. 504,100. (No model.)

To all whom it may concern:

Be it known that I, ARTHUR THYLL, a citizen of Austria-Hungary, and a resident of New York, in the county of New York and State of New York, have invented certain new and useful Improvements in Electric Cloth-Cutting Machines, of which the following is a specification.

My invention relates to machines for cutting cloth and like material.

In the apparatus hereinafter described embodying my invention, two serrated knife blades are alternately moved up and down by means of mechanism hereinafter fully described.

My invention is particularly pointed out in the claims.

In the accompanying drawings, Figure 1 represents a side view of my improved cloth cutting machine. Fig. 2, is a vertical section on line $x-x$, and Fig. 3, a horizontal section on line $y-y$, Fig. 1. Fig. 4, is a horizontal section on line $z-z$ Fig. 2, and Fig. 5, is a detail side view showing the mechanism for moving the knife blades up and down.

Similar letters of reference indicate corresponding parts.

The casing of the machine is formed by the two pole-pieces A' and A, and the two field-coils B and B'; the latter shown in Fig. 3. Between the two pole pieces the armature C is arranged, which produces in connection with the pole-pieces, the magnetic circuit of the motor. Brackets D and D' are screwed respectively, to the top and the bottom of the pole-pieces and serve as bearings for the shaft E of the motor to which shaft the electric commutator E' is fastened. The bracket D carries the brush-holder, which is secured to the same in any suitable manner. The commutator and the bracket thereof, are inclosed by a dome-shaped cap F, which is provided with a wheel-shaped handle F'. The lower bracket has vertical guide-holes, as shown in Fig. 5, in which sliding pins d, are movably fitted. These sliding pins carry the angularly bent sliding pieces G and G', which are provided with inwardly extending pins g g', reaching a screw shaped groove in the rim of

a wheel H, that is keyed to the motor-shaft E, 50 as clearly shown in Figs. 2 and 5.

By the rotary motion of the shaft E and the screw-wheel H, the sliding pieces G and G' are moved up and down as the guide pins g and g' of the said sliding pieces follow the up and down-ward motion of the guide-groove of the screw-wheel. The angle portions of the sliding pieces G and G' meet each other and have each a serrated knife blade h h', screwed or otherwise attached thereto. The 60 indentations of the knife blades are so made that one edge of the same is vertical and the other angular to the length of the blades. Only the angular edges are sharpened outside of the blades, so that the inner sides of the blades are perfectly straight and the whole inner surfaces of the same slide on each other.

The knife blades which are secured to the angular sliding pieces G G', are alternately drawn up and down by the like movement of the said sliding pieces imparted to the latter by the screw wheel H. The screw-wheel, as well as the angular sliding pieces are inclosed by a conical cap J, screwed or riveted to the pole pieces, covering also the 70 bracket D'. To the lower end of the cap J, a standard K is attached that is fastened to the base-plate L, by means of screws or rivets. The standard K has a vertical groove in which the knife blades are so fitted that 80 the indentations of the same project out of the same. Three or more balls M, are so inserted into the base plate, that they form rollers for the same and allow any motion of the machine.

A handle N, is attached to the back-side of the machine, which serves to push the machine toward the pile of cloth to be cut. The electric current to put the machine into motion, is conducted from the generator to the motor through the conducting wires running through a longitudinal bore of the handle N to the switch O and from there through conducting wires within the tube P, to the terminals of the motor.

The cutting of the cloth with my improved cutter is performed in the following manner: The base-plate of the machine is pushed below

the pile of cloth and by means of the switch O the electric current is conducted to the motor and the shaft E with the screw shaped guide wheel H put into rotary motion. The groove 5 in the rim of the said guide wheel, engaging the guide pins of the angular guide pins G G', causes the latter and simultaneously therewith the serrated knife blade within the groove of the standard K to move alternately up and down, so that the knife blades by their reciprocating motion act like the blade of scissors and cut into the cloth. By means of the handle, the machine is moved along in the cloth according to the pattern to be cut.

15 If it is desired to cut sharp corners, the machine may be moved by means of the hand-wheel on top of the dome. The roller balls within the base plate allow the operator to move the machine easily in any direction.

20 My improved cutting machine has the advantage that sharp corners can be cut with the same, which cannot be done with the disk cutters now in use.

Having thus described my invention, I 25 claim as new and desire to secure by Letters Patent—

1. In a cloth cutting machine, an electric motor mounted on a standard having a base-plate, the rotating shaft of which motor is pro- 30 vided with a screw-shaped guide-wheel having a groove in its rim, in combination with angular guide-pieces loosely fitted in a bearing and having guide-pins engaged by the said guide-wheel to move alternately up and

down, and serrated knife-blades attached to 35 the angular guide-pieces, substantially as set forth.

2. In a cloth cutting machine, the combination of an electric motor, with a casing inclosing the same, a rotary shaft of the motor 40 with bearings therefor, a screw-wheel mounted on the said shaft, angular guide-pieces having knife-blades attached thereto, guide-pins attached to the angular guide-pieces and being engaged by the said screw-wheel, and a 45 grooved standard fastened to the base-plate, in which standard the knife-blades are alternately moved up and down by the rotary motion of the motor-shaft, substantially as set forth.

3. In a cloth cutting machine, the combination of the rotating shaft E having the guide-wheel H keyed thereto, with the bracket D', the angular guide-pieces G G' having pins d d loosely fitted in the bracket D', guide- 55 pins g g' engaged by the said screw-wheel and vertically movable knife-blades h h', the cap J, and the grooved standard K inclosing the knife-blades and being attached to the said cap and the base-plate of the machine, 60 substantially as set forth.

Signed at New York, in the county of New York and State of New York, this 4th day of November, A. D. 1891.

ARTHUR THYLL.
